UNITED STATES PATENT OFFICE

FRED E. SMITH, OF SANTA PAULA, CALIFORNIA

VALVE SEAT

Application filed October 23, 1926. Serial No. 143,660.

This invention aims to provide novel means for holding in place a valve seat in a cylinder head or other part of the frame of an internal combustion engine, the device being of peculiar utility in connection with renewing the seat for a poppet valve in an internal combustion engine.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:

Figure 1 shows in section, a part of an engine frame wherewith the device forming the subject matter of this application has been assembled, parts appearing in elevation;

Figure 2 is a transverse section taken through the seat for the valve.

The numeral 1 marks any suitable part of the frame of an internal combustion engine, the piston appearing at 2 and the poppet valve at 3, the valve being carried by a stem 4 mounted to reciprocate in the frame 1.

When it becomes necessary to renew the seat for the valve 3, an annular recess 5 is formed in the frame 1, the outer wall of the recess 5 being provided with a continuous circumferential groove 6. The seat 7 is in the form of a ring and is internally beveled as at 8 to cooperate with the bevel 9 of the valve 3. The seat or ring 7 has a very close fit, perhaps a driving fit, in the recess 5, and this, of itself, aids in holding the seat or ring 7 in the recess. An additional or positive means is supplied for retaining the valve seat 7 in the recess 5, and with this end in view, the seat ring 7 is supplied on its outer surface with a continuous circumferential

groove 10. This groove 10 is located at such a distance from one end surface 11 of the seat ring 7 that, when the surface 7 abuts against the wall 12 of the recess 5, the groove 10 in the seat ring 7 will be disposed directly opposite to the groove 6. Before the seat ring 7 is inserted into the recess 5, the groove 6 and the groove 10 are filled with a cement which will harden, the cement being refractory, so that it will withstand the heat of internal combustion. After the seat ring 7 is placed in the recess 5, in the position shown in Figure 1, the cement in the groove 10 coalesces with the cement in the groove 6 to form a continuous ring 14 of cement which is interlocked or interengaged with the seat 7 and with the frame 1 of the engine, to hold the seat 7 in place.

What is claimed is:

1. In an internal combustion engine, a valve housing formed with a recess, a valve seat member adapted for close fit reception within said recess, both said valve seat member and said valve housing being formed with complementary grooves, the valve seat member in its operative position within said recess having contact at its side with the side wall of said recess at both sides of said grooves, and a cement confined between said grooves for locking the seat to the said valve housing.

2. In an internal combustion engine, in combination, a valve housing formed with a recess, the wall defining the side of said recess having a groove opening into said recess, a shoulder at the inner end of said recess, and a valve seat member adapted for a disposition within said recess, said valve seat member being of a size to snugly fit said recess and when operatively disposed therein having its inner end abutting said shoulder and its side engaging the side wall of the recess at both sides of the groove in said side wall, said valve seat member having an exterior side groove disposed for alinement with the first mentioned groove when the inner end of the valve seat member is disposed against said shoulder, whereby separate bodies of plastic cement which are adapted to be placed in the respective grooves prior to inserting the valve seat member in the recess are adapt-

ed to unite with one another to form a lock to retain the valve seat member in the recess.

3. In combination, a valve housing formed with a recess, the wall defining the side of
5 said recess having a groove opening into said recess, and a valve seat member adapted for disposition within said recess, said valve seat member being of a size to snugly fit said recess and when operatively disposed therein
10 having its side face engaging the side wall of said recess at both sides of the groove in said side wall, said groove being adapted to receive cement for retaining the valve seat member within said recess.
- 15 4. In combination, a valve housing formed with a recess defined in part by a side wall, and a valve seat member adapted for disposition within said recess, said valve seat member having a groove opening through the side
20 face thereof and said member being of a size to snugly fit said recess and to contact at its side with the side wall of the recess at both sides of said groove when said member is operatively disposed within said recess, said
25 groove being adapted to receive cement for retaining the valve seat member within said recess.

In testimony that I claim the foregoing as my own, I have hereto affixed my signature.

FRED E. SMITH.
